UNITED STATES PATENT OFFICE.

GEORGE W. B. SMITH, OF POMONA, ILLINOIS.

TENSION DEVICE FOR GRAIN-BINDERS.

SPECIFICATION forming part of Letters Patent No. 352,429, dated November 9, 1886

Application filed April 6, 1886. Serial No. 197,998. (No model.)

To all whom it may concern:

Be it known that I, GEORGE W. B. SMITH, a citizen of the United States, and a resident of Pomona, in the county of Jackson and State 5 of Illinois, have invented certain new and useful Improvements in Tension Devices for Grain-Binders; and I do hereby declare that the following is a full, clear, and exact description of the invention, which will enable others skilled 10 in the art to which it appertains to make and use the same, reference being had to the accompanying drawings, which form a part of this specification, and in which—

Figure 1 is a perspective view of my improved tension device for grain-binders. Fig. 15 2 is a side view of the same, and Fig. 3 is a longitudinal vertical sectional view of the same.

Similar letters of reference indicate corresponding parts in all the figures.

My invention has relation to tension devices for regulating the tension of the binding twine or wire for grain-binders; and it consists in the improved construction and combination of 25 parts of the same, as hereinafter more fully described and claimed.

In the accompanying drawings, the letter A indicates a portion of the frame of the binder upon which the device is secured, and this 30 portion of the frame is provided with a slot or recess, B, the function of which shall be hereinafter described. A bracket, C, is secured upon the upper side of the base, and is formed with a rear flange, D, and with two side or 35 end flanges, E and F, one of which is provided with a perforation, G, while the other flange or lip is provided with a notch or slot, H, opening in the forward edge of the flange. A shaft, I, rocks with its ends in the bearings 40 formed by the perforation and by the slot, and an L-shaped arm, J, is secured to the shaft by its horizontal lower arm, having its other arm bent at a right angle thereto and projecting vertically upward. A spring, K, is coiled 45 around the shaft and is secured at one end to the slotted end flange, while the other end of the spring is secured to the inner end of the elbow-arm, the inner end of which projects to the rear of the shaft and rests upon the upper 50 edge of the rear flange, when the arm is in its normal position, in which the spring serves to

keep it. A box, L, slides upon the upwardly-bent portion of the arm, and is provided with a set-screw, M, by means of which it may be adjusted upon the arm, and a sheave, N, is 55 journaled upon a stud, O, projecting from the side of the sliding box.

The binding twine or wire P passes through a number of eyes, Q, at both sides of the flanged bracket and passes over the grooved sheave, 6c and it will be seen that as the twine or wire passes over the said sheave and any strain comes upon the same the arm will be tilted downward against the tension of the spring, which will force the arm back into its normal 65 position as soon as the increased strain has passed, and the slot in the base is provided for the purpose of allowing the pulley to turn freely when the arm is tilted entirely down.

The sheave or pulley may be moved farther 70 up or down upon the arm by means of the set-screw to adjust the said pulley, and thus the leverage with which the strain of the twine or wire is exerted upon the arm may be increased or decreased by moving the pulley farther up 75 or down upon the arm. In this manner all slack upon the twine or wire during the operation of the binder may be taken up, and all undue strain upon the wire or twine be prevented by the yielding arm having the pulley 8c over which the twine or wire passes, the device thus insuring a perfectly-tight binding of sheaves of different thickness and preventing breaking of the twine or wire.

Having thus described my invention, I claim 85 and desire to secure by Letters Patent of the United States—

1. In a take-up and tension device for grain-binders, the combination of an arm projecting from a shaft having its ends suitably journaled 90 in a support, a spring coiled around the shaft, and secured at one end to the arm and at the other end to one of the bearings of the shaft, and a pulley having the binding twine or wire passing over it and journaled upon a stud projecting from a box sliding adjustably upon the arm, as and for the purpose shown and set forth.

2. In a take-up and tension device for grain-binders, the combination of the base having 100 the slot, the bracket having the rear flange, and one end flange having a perforation and

another end flange having a slot, a shaft journaled with its ends in the perforation and slot, an L-shaped arm secured to the shaft and having the rear end of its horizontal portion resting upon the rear flange, a spring coiled around the shaft and secured to the rear end of the arm and to the slotted end flange, a box having a set-screw and sliding upon the upper portion of the arm, and a pulley journaled

upon the side of the box, as and for the purpose shown and set forth.

In testimony that I claim the foregoing as my own I have hereunto affixed my signature in presence of two witnesses.

GEORGE W. B. SMITH.
